BOTTLE CARRIER

Harry Z. Gray, Lebanon, Ohio

Application September 11, 1948, Serial No. 48,789

9 Claims. (Cl. 294—87.2)

1

This invention relates to bottle carriers, and in particular to carriers of the type which are designed to engage bottle necks for the principal support of the bottles.

In my prior Patent No. 2,187,494 is shown a carrier of this type which has a central, handle portion and two flaps extending therefrom, each having a double layer and staggered openings in the layers whereby the openings function as bottle-neck grippers as the flaps are manipulated in dihedral angular motion.

The present invention employing only a single set of flaps, operating in the manner of the covers of a book, achieves easier manipulation without sacrifice to security and reduces manufacturing costs both in respect to time and material.

It is therefore an object of the invention to provide a bottle carrier simplified in form and function and which results in reduced manufacturing costs. More particularly, it is an object to provide a bottle carrier which combines in a single set of flaps the bottle-gripping features and a handling element.

These and other ends which will in part be apparent and in part made manifest as the description proceeds are realized by the invention, preferred forms of which are described in the accompanying specification and illustrated in the drawings, in which:

Fig. 1 is a view in perspective of one form of carrier in folded, bottle-gripping position, and with a complement of bottles indicated in phantom,

Fig. 2 is a plan view of the carrier of Fig. 1, somewhat enlarged and in open position,

Fig. 3 is a partial plan view of the carrier of Fig. 2 in folded condition,

Fig. 4 is a section taken on the line 4—4 of Fig. 3,

Figs. 5, 6, 7 and 8 are views similar to Figs. 1, 2, 3 and 4 respectively showing a modified carrier, and

Fig. 9 is a view in perspective showing the manner of initiating disengagement of the carrier from a group of bottles.

Referring to the drawings by characters of reference, there is shown in Fig. 2 a set of flaps 10, 11 united along an edge 12 which is scored as at 13 to facilitate folding of the flaps into face-to-face contact. A pair of identical, tapered ends 15, 16 are provided with openings 17, 18 which are superimposed in the folded condition of the carrier and which accommodate the fingers of a user for carrying purposes.

The main body portions of the flaps are provided with openings preferably in an orderly arrangement of columns and rows. In flaps 11 these comprise a semicircular boundary 20 and a flat-bottomed U-shaped boundary 21, wider than the diameter and deeper than the radius of boundary

2

20. Flap 10 is provided with openings having nearly semicircular boundaries 22 which, in the folded condition of the carrier mate with boundaries 20 to define a complete circular opening of a size to fit around the neck of a bottle in an engagement which will not pass the usual annular collar 25 provided on bottle necks. The opposite boundary 23 of the openings in flap 10 is eccentric to and of larger diameter than opening 22, and is of sufficient size to pass collar 25 of a bottle without forcing.

In use, a set of bottles is lined up in the general pattern of the openings in the flap, if not already so lined up on a shelf or in a box, and openings 23 are passed down over the bottle necks beyond collar 25. Flap 11 is then folded down onto flap 10, openings 21 clearing collars 25 in their swinging movement. These two movements complete the necessary manipulation and the carrier and contents are ready to be picked up by the handle 15, 16. To remove the carrier it is only necessary to reverse the steps, unfolding flap 11 and then lifting flap 10. By providing a folding carrier with a hinge at an edge, I have succeeded in reducing the curvature of the swing of the openings adjacent the free edges which enables a reduction in dimensions of the collar-clearing opening. The unreduced curvature of swing for the openings adjacent the hinge is compensated by the increased leverage afforded by the flap.

In the opening movement of the flap it has been found expedient to initiate the same by action at the handle portions of the flaps. In this way, action is initiated at the outer opening which is nearest the handle and the balance of the outer openings are disengaged from the bottle neck in rapid succession, thus providing economies in the opening effort.

Another very important feature of the carrier of this invention is that it enables the provision of a hand grip having its long dimension parallel to the long dimensions of the bottle-receiving openings. This arrangement ensures that the stresses on the carrier openings incident to relative tilt of bottles and carrier will occur on a diameter having solid backing by both flaps and not subject to any displacements of the carrier layers and attendant increase in the effective size of an opening.

In order to ensure that the upper flap will not disengage automatically by any tendency to unfold when not held in the hand, I provide a locking device comprising a struck tab 26 in one of the flaps, swingable about a scored line 28 as a hinge and having ears 27 at its ends. The central portion of tab 26 is dimensioned to pass through a recess 29 in the other flap whereby to engage ears 27 behind the edge margins of the recess by forcing.

A further refinement consists in providing

scored lines 30, 31 aligned with the hand-grip openings 17, 18 respectively, to accommodate the natural angle which the carrier will assume in respect to the center of gravity of the complement of bottles.

In Figs. 5 to 8 is shown a carrier generally similar to the one just described, but modified for the purpose of carrying larger sizes of bottles, those of 24 ounce capacity for instance. In these views the bottle-engaging openings are identical with those in Fig. 2 and are therefore indicated by the same reference numerals. These are four in number and arranged in a square pattern in flaps 30, 31. The hand opening is arranged centrally of the carrier in alignable openings 32, 33. The flaps are integral along an edge, foldable by means of a score line 34. A locking tab 36 is engageable in a slot 37. This carrier may have an extra layer 38 on the bottom flap for reinforcement. It will be noted that in this modification, also, the handle is also aligned with the long dimensions of the small openings. While the slanting is not as acute where the handle is centrally of the carrier, nevertheless the slanting tendency is present.

One of the features which distinguish the invention from known carriers is the provision of the handle within the flap portion. This not only permits a compact organization with reduced manufacturing costs, but also facilitates the process of opening the flaps to release a set of bottles, since the region of application of the opening force is always ready to hand at the end of a carrying operation and does not involve depositing the package and shifting the fingers to another point to open. Furthermore the high leverage resident in the flaps coupled with the single thickness at the hinge ensures the maintenance of disengagement after it is effected.

While certain preferred embodiments have been shown, the invention is not limited thereby, but only as shall appear from the spirit and scope of the appended claims.

What is claimed is:

1. A carrier for bottles comprising a pair of planiform flaps united in a common edge for folding one flap upon the other, a series of openings in each flap, each opening being elongate in a direction transverse to the said common edge, and the openings in one flap alignable in part with, but being staggered with respect to the openings in the other flap in said direction, in the folded condition of the flaps, and openings in the said flaps, aligned in the folded position of the flaps to provide a manual carrying means.

2. A carrier for bottles comprising a pair of planiform flaps united in a common edge for folding one flap upon the other, a series of openings in each flap arranged in plurality, both in a direction transverse to the said common edge, in a direction parallel to the said common edge, each opening being elongate in a direction transverse to said common edge, and the openings in one flap being alignable in part with but being staggered in the folded condition of the flaps, with respect to the openings in the other flap in the direction transverse to the said common edge, and openings in the said flaps, aligned in the folded position of the flaps to provide a manual carrying means.

3. A carrier for bottles comprising a pair of planiform flaps united in a common edge for folding one flap upon the other, openings in the flaps alignable upon folding thereof to lock around the necks of bottles, and openings in the

respective said flaps aligned in the folded position of the flaps and dimensioned to receive the hand of a user for carrying purposes.

4. A carrier for bottles comprising a pair of planiform flaps united in a common edge for folding one flap upon the other, openings in the flaps alignable upon folding thereof to lock around the necks of bottles, and openings in the respective said flaps aligned in the folded position of the flaps and being elongate to receive the fingers of a user, the elongate direction of said latter openings extending transversely to said common edge.

5. A carrier for bottles comprising a pair of planiform flaps united in a common edge for folding one flap upon the other, openings in the flaps alignable upon folding thereof to lock around the necks of bottles, and openings in the respective said flaps aligned in the folded position of the flaps and being elongate to receive the fingers of a user, the elongate direction of said latter openings extending transversely to said common edge and being adjacent a pair of edges of said flaps, transverse to said common edge.

15 6. A carrier for bottles comprising a pair of planiform flaps united in a common edge for folding one flap upon the other, openings in the flaps alignable upon folding thereof to lock around the necks of bottles, and openings in the respective said flaps aligned in the folded position of the flaps and adapted to receive the fingers of a user for handling purposes, said latter openings lying intermediate the first mentioned openings.

30 7. A carrier for bottles comprising a pair of planiform flaps united in a common edge for folding one flap upon the other, openings in the flaps alignable upon folding thereof to lock around the necks of bottles, and elongate openings in the said flaps, aligned in the folded position of the flaps to accommodate the fingers of a user, said last-mentioned openings lying intermediate the first-mentioned openings and having their long dimension transverse to the said common edge.

40 8. A carrier for bottles comprising a pair of planiform flaps united in a common edge for folding one flap upon the other, openings in the flaps alignable upon folding thereof to lock around the necks of bottles, openings in the respective said flaps aligned in the folded position of the flaps to receive the fingers of a user, and means to releasably lock the flaps in folded position.

45 9. A carrier for bottles comprising a pair of folding flaps, openings in the flaps to lock around the necks of bottles, and openings in the said flaps defining a handle located adjacent to edges of the flaps transverse to the line of fold.
